AUTOMATIC TRAIN PIPE CONNECTER

Joseph Robinson, New York, N. Y., assignor of
one-half to Roy M. Wolvin, Montreal, Quebec,
Canada

Application November 6, 1930, Serial No. 493,877
Renewed August 25, 1933

4 Claims. (Cl. 285—58)

This invention relates to automatic train pipe connectors and particularly to the universal joint in supporting such connectors for free universal movement whereby they may accommodate themselves to the various positions cars assume in service.

In my copending application Serial #394,856 filed September 24th, 1929 is shown a universal joint of the type of which the present construction is an improvement. It sometimes happens, in cases of extreme coupler slip-bys, that the automatic connector head and body will be turned to a position at a right angle to the track. Sometimes when the head and body are moved to this position, the head is also shoved upwardly. This upward movement of the head throws the rear end 10 of the pipe or body (see Figures 3 and 4 of my above copending application) downwardly allowing the lugs or shoulders 12 to enter the opening 18 in the end 10 of the pipe or body of my said copending application. It sometimes happens that at the same time the head 16 of the tie rod of the construction in my copending application rolls or drops to the position shown at 25 5 in Figure 3 of the accompanying drawing. When in this condition the connector body or pipe cannot of course automatically return to the normal position. If while stuck in this crosswise position the connector extends across the pipe or body of the connector on the opposite car, then when the two cars are parted the head of the crosswise connector will foul behind the head of the other connector, and since its pipe cannot swing in the universal joint, while stuck as just described, the universal joint or lower portion of the bracket will be twisted causing some damage.

It is the object of the present invention to avoid this possibility. The structural improvements by which these are accomplished are illustrated in the accompanying drawing in which

Figure 1 is a sectional side elevation of an automatic connector having my improved universal joint;

Figure 2 is a sectional plan view through the universal joint and a part of the connector body this section being taken on the line 2—2 of Figure 1. In this view the connector body is shown turned at a right angle to the track, the position in which the universal joint and body would become locked together except for improvements described in this application;

Figure 3 is an elevation of the lower end of the bracket shown in Figure 1 slightly modified. In this view the tie rod seat on the bracket is off-set rearwardly, and the tie rod head is shown in sec-

tion. In this view is also shown the hereinbefore described position the tie rod head sometimes gets into under the influence of extreme coupler slip-bys;

Figure 4 is a sectional plan view of the lower end of the bracket showing my improved universal joint and tie rod assembly, and

Figure 5 is a face view of the lower end of the bracket with the flanges or webs 15 and 16 omitted, and illustrating the objectionable position of the member B which the present invention aims to prevent.

With the present construction the fouling of the pipe or body of the connector and the universal joint cannot occur. The lower end 6 of the bracket A is disposed approximately vertically and is round in cross section. It is provided with upper and lower transversely extending abutments or shoulders 7 and 8 similar to the shoulders 12 of my aforesaid copending application. Midway between its length the portion 6 is provided with a curved or flared seat 9 for the similarly shaped hollow head or eye 10 of the tie rod 11. The seat includes horizontally disposed annular rings or shoulders 12 and 14 and are preferably arranged eccentrically as shown particularly in Figure 2. The cross members or shoulders 7 and 8 are provided with forwardly extending curved flanges 15 and 16 employed to give enlargement to the outer ends 80 of the shoulders and prevent their entering the opening 17 in the rear end of the pipe or body B of my improved connector when the body is moved to a position at a right angle to the track shown in Figure 2 and hereinbefore described. 90

The shoulders 15 and 16 are curved and are extended forwardly of the portion 6 in order to produce an eccentric surface, when the connector body B and universal joint are in the position shown in Figure 2, which will enable 95 the buffer spring C to automatically throw or return the body B, and in consequence the coupling head D to the normal position shown in Figure 1. The lower end 6 of the bracket A is positioned between the straps 18 and 19 of the body B. In other words it is spanned by the body B. The head 10 of the tie rod 11 is provided with a perforation of sufficient length and width as to freely permit it to be passed over the projections 8 on the lower end of the bracket and 100 moved upwardly over the annular ring or shoulder 14 and into its seat 9 on the portion 6. The forward end 20 of the tie rod is flared in opposite directions to the flare of the seat 9. The curve in this portion 20 where it contacts with 110

the anchor lug 6 of the bracket may either follow the curve of such lug, as shown in the drawing, or the curve thereon may extend from the inner walls of the perforated tie rod head 10 5 and encircle the portion 6. As shown the said inner walls are offset away from the curve of the head 20 as shown at 21, but these offsets may, as stated, be eliminated if desired. The lower end of the bracket shown in Figure 3 10 differs from the bracket shown in Figure 1 only to the extent that the seat 9 and portion 6 in the Figure 3 construction are offset rearwardly. With this construction the annular shoulders 12 and 14 need not extend entirely around the portion 6 as the indented seat 9 on the front face 15 of the portion 6 in this construction serves to support the forward end 20 of the tie rod 11. It will be obvious that with this construction, as in the case of the other embodiment illustrative 20 of my invention, the tie rod head cannot fall to the position shown in dotted lines at 5 in Figure 3 when the connector body B moves to the position shown in Figure 2. The opening 17 in the rear end of the body B is of less dimension 25 vertically than laterally which means additional insurance against the cross members 7 or 8 entering the opening under the conditions previously described. It will be understood that the shoulders or abutments 7 and 8 of the bracket A, 30 in cooperation with the inclined rear portions 22 of the straps 18 and 19 of the body B, serve to position the body on the bracket and prevent undue rotation thereof relative to the bracket. In case the spring C or tie rod 11 should break, 35 the lower projection or shoulder 8 serves to prevent dislocation of the pipe or body B from the bracket.

It sometimes happens that the rear end of the pipe or body B, when the universal joint is constructed as shown in my aforesaid copending application, gets into the position indicated in Figure 5. The coupler slips by and shoves the body to a position at a right angle to the track and tilts the coupling head and body upwardly, causing the flange 23 to ride or climb up on the lower cross member or abutment 8 of the bracket A, and the straps 18 and 19 to straddle the upper lug 7 of the bracket. This fouling of the parts is effectually prevented by adding some additional metal to the bottom of the pipe flange, as shown at 23' in Figure 1. In other words, the flange 23 extends downwardly to such an extent as to prevent the lower edge thereof from crawling or riding up into the position shown in Figure 5, and in consequence the ribs or enlargements 15 and 16 on the cross members or lugs shown especially well in Figures 2 and 4 may be omitted. The retaining walls or projections 12 and 14 may be limited to the front and rear 60 faces of the anchor lug 6 in which case the opening in the tie rod head 10 may be narrower than shown.

What I claim is:

1. An automatic train pipe connector comprising, in combination, a coupling head, a bracket, a member extending rearwardly from the head and having parts spanning the bracket, said bracket having laterally extending abutments above and below said member and cooperating therewith to support the same on the bracket, said bracket also having a seat disposed between the parts of said member, a flange or projection connecting the rear ends of said spaced parts of said member, said flange having an opening 75 therein, a tie rod extending from the rear of

said bracket and through said opening and embracing said seat, a spring carried by said tie rod, means on said bracket to maintain said tie rod in a substantially horizontal position when the same and said member are moved to extreme lateral positions around said bracket, the opening in said flange being of such size with respect to said tie rod as to prevent upward movement of said flange above the lower abutments on said bracket when said member and tie rod are moved to extreme lateral positions, whereby fouling of said member on said laterally extending abutments is prevented. 80 85

2. An automatic train pipe connector comprising, in combination, a coupling head, a bracket, a member extending rearwardly from the head and having parts spanning the bracket, said bracket having laterally extending abutments above and below said member and cooperating therewith to support the same on the bracket, said bracket also having a seat disposed between the parts of said member, a flange or projection connecting the rear ends of said spaced parts of said member, said flange having an opening therein, a tie rod extending from the rear of said bracket and through said opening and embracing said seat, a spring carried by said tie rod, means on said bracket to maintain said tie rod in a substantially horizontal position when the same and said member are moved to extreme lateral positions around said bracket, the opening in said flange being of such size with respect to said tie rod as to prevent extreme upward movement of said flange, and the lower portion of said flange extending downwardly to 100 such an extent as to prevent the lower edge thereof from riding up on the lower projections on said abutment when said member is moved to said extreme lateral positions around the bracket. 105 110 115

3. An automatic train pipe connector comprising, in combination, a bracket, a head supporting member spanning said bracket, said bracket having laterally extending abutments above and below said member and cooperating therewith to support the same on the bracket, said bracket also having spaced shoulders formed thereon between said abutments and extending laterally thereof, whereby a seat is formed between said shoulders, a flange connecting the rear ends of said spaced portions of the head supporting member and arranged to bear against said abutments, said flange having an opening therein, a tie rod extending from the rear of said bracket through said opening and embracing said seat between said shoulders, a spring carried by said tie rod and bearing against said flange, said shoulders serving to support said tie rod in a substantially horizontal position when the tie rod and head supporting member are moved to extreme lateral positions around the bracket, said opening in said flange being of such size that the lower part of said opening will contact with said tie rod to thereby prevent upward movement of said flange to such an extent as to permit the lower edge thereof to ride up on said lower abutments on the bracket. 120 125 130 135 140

4. An automatic train pipe connector comprising, in combination, a coupling head, a bracket, a member extending from the head and having parts spanning the bracket, said bracket having laterally extending abutments above and below said member and cooperating therewith to support the same on the bracket, said bracket also having a seat, a flange connecting the rear ends of

said spaced parts of said member, said flange having an opening therein, a tie rod extending from said bracket and through said opening and embracing said seat, a spring carried by said tie rod, means on said bracket to maintain said tie rod in a substantially horizontal position when the same and said member are moved to extreme positions around said bracket, the open-

ing in said flange being of such size with respect to said tie rod as to prevent upward movement of said flange above the lower abutments on said bracket when said member and tie rod are moved to extreme positions, whereby fouling of said member on said extending abutments is prevented. 80
